UNITED STATES PATENT OFFICE.

PETER J. CHRISTMAN, OF GREEN BAY, WISCONSIN.

INTERFOLDING MACHINE.

Application filed October 22, 1927. Serial No. 228,004.

This invention relates to interfolding machines, and is particularly directed to a machine for interfolding sheets of paper which have previously been folded along two lines 5 at right angles to each other.

This invention is an improvement over that disclosed in my Patent No. 1,637,550 of August 2, 1927, for interfolding machines, and over the invention disclosed in my co- 10 pending application, Serial No. 201,699, filed June 27, 1927, for interfolding machines.

In dispensing paper napkins it is the usual practice to quarter fold the napkins, that is to say, to fold them along two lines 15 at right angles to each other. No satisfactory means has heretofore been devised for interfolding these already folded paper napkins with the consequence that the napkins are usually stacked one above the other 20 without interfolding and consequently dispensing is difficult. As far as I am aware, no successful machine has been produced and no successful method evolved for inter- folding these already folded paper napkins.

25 This invention is designed to provide a machine and a method for first folding the napkin longitudinally, thereafter transversely, and subsequently interfolding this doubly folded napkin so that it may be stacked in a very compact form and readily dispensed.

30 A further object of this invention is to provide a novel form of interfolded or stacked doubly folded napkin in which the exposed flap is of double thickness only, as distinguished from quadruple thickness.

35 Further objects are to provide a machine which will continuously longitudinally fold, sever, transversely fold and interfold the 40 severed sheets in a highly effective and rapid manner.

An embodiment of the invention is shown in the accompanying drawings which diagrammatically illustrate the invention:—

45 Figure 1 is a diagrammatic view of the entire machine with parts in section;

50 Figure 2 is an enlarged fragmentary and diagrammatic sectional view of the creasing and vacuum rolls for stripping the trans- versely folded sheets from the carrier cylinder or roller;

Figure 3 shows the form of the sheet as it is carried by the carrier roll;

55 Figure 4 shows the form of sheet as it passes between the creasing rolls;

Figure 5 is a diagrammatic view showing

the position of the holders and tucker blades in the next stage after that illustrated in Figure 1;

Figure 6 shows the successive stage or position of the parts;

Figure 7 shows the final stage of the parts.

Referring to the drawings, it will be seen that the paper is fed downwardly in a sheet 1 which passes over the former plate 2 and which is thus longitudinally creased as it passes between the puller rolls 3. If desired, guide plates 4 may be positioned just outside of the edges of the former plate 2. The longitudinally folded sheet passes to the carrier cylinder or roll 5 and a cut off roll 6 cooperates with the carrier roll. This cut off roll is provided with a tucker blade 7 adapted to press the longitudinally folded sheet into depressions 8 formed in the carrier roll 5. It is also provided with a cut off knife 9 cooperating with cut off slots 10 formed in the carrier roll.

Below the carrier roll, the creasing rolls 11 and 12 are positioned. One of the creasing rolls, for example, the roll 12, is provided with a suction aperture 13 at which vacuum is produced at periodic intervals to grip the sheet and draw it down between the rolls 11 and 12 in a well known manner. This drawing of the sheet from the carrier roll is shown most clearly in Figure 2.

The apparatus for producing the longitudinal fold may be such as that disclosed in my prior Patent No. 1,481,252 of January 22, 1924, for sheet folding machines, and the creasing rolls may be of the type disclosed in my Patent No. 1,566,079 of December 15, 1925, for rotary sheet folder.

It is to be noted that the paper passes more than half way before the suction aperture 13 withdraws the paper from the carrier roll, as shown in Figure 2, so that the fold is not made transversely directly in the center of the severed and longitudinally folded sheet, but is so made that approximately two-thirds of the finally folded sheet is of quadruple thickness, and one-third of double thickness, as is apparent from Figure 1. This showing in Figure 1 discloses the double thickness as a single line for the reason that the folded edge of the paper is presented towards the observer. This same mode of showing is followed in Figures 5, 6, and 7, to avoid needless complication and to make the showing consistent.

The doubly folded sheet passes down-

wardly between the guideways 14 to the interfolding mechanism. This interfolding mechanism may comprise a stationary holder 15 provided with a front lip 15' and a movable holder 16, provided with a front lip 16'. This movable holder may be rocked back and forth at regular intervals in any suitable manner as by means of the rack 17 and the pinion 18, the pinion being actuated 10 by a rack bar 19 connected with a crank 20. The crank 20 is carried by the shaft 21 which is connected by suitable gearing, as set forth in my above noted patents and applications, with a main shaft 22 which carries 15 a main cam 23. This main cam actuates the tucker blade arms or levers 24 and 25 and preferably through the medium of the cam followers or rollers 24' and 25' carried by the respective levers. These tucker 20 blade levers are provided with tucker blades 26 and 27 which will hereinafter be referred to as the upper and lower tucker blades, although this mode of describing them is employed merely for simplicity, and is not 25 to be interpreted in a limiting sense.

From the description thus far given, it will be seen that the doubly folded sheets pass down the guides 14 to the holders 15 and 16, and that these sheets are folded both 30 longitudinally and transversely. The transverse fold is such that it leaves a free or extended lip, as may be clearly seen from Figures 1, 5, 6, and 7. After the sheet has arrived at the position shown in Figure 1, 35 the bottom holder 16 travels inwardly, as shown in Figure 5. The position of the parts are now as shown in Figure 5 with the upper tucker blade 26 in its raised position. The lower tucker blade 27 rises and 40 tucks the sheet in back of the lip 15' of the upper holder, as shown in Figure 6, and at the same time, the end of the sheet or tail of the sheet is swept from the guide. Thereafter, the bottom tucker blade descends and 45 the holder 16 moves outwardly and the upper tucker blade begins to descend, as shown in Figure 7. This extends the outer or lip end of the sheet outwardly, as shown in such figure, and as the upper tucker blade 50 26 completes its downward motion a new sheet is slid into place along the guides 14, as shown in Figure 1.

The result of this mode of folding or mode 55 of operation is to produce an interfolded package in which layers, A, B, C, (see Figures 5 to 7) are produced. It is to be noted that the layer A is of double thickness and the layers B and C are of quadruple thickness, it being understood as previously explained 60 that the single line showing in Figures 1 to 7, is due to the fact that the observer is looking at the folded edge of the longitudinally folded sheet. Further, it will be noted that the thinnest layer A is 65 interposed between two quadruple thickness

layers. This prevents excessive bulging of the package on the one hand and also facilitates dispensing of the folded napkins, as will immediately appear. For example, when the folded napkins are put into a container, the extended or free leaf or layer is always the double ply layer, not the quadruple ply layer. This gives greater flexibility and permits easier withdrawal of this extended portion and consequently of the entire folded napkin. The withdrawal of the folded napkin from a container obviously withdraws or projects the extended double 75 ply layer of the succeeding napkin.

It will be seen that a novel form of interfolding machine has been provided in which the napkins are folded longitudinally and transversely and are thereafter interfolded in a novel manner to provide a stack of napkins having interfolded portions and so arranged that they may be placed in an ordinary dispenser and may be easily withdrawn therefrom.

It will be seen further that the machine is relatively simple and is reliable in operation.

Although the invention has been described in considerable detail, such description is intended as illustrative rather than limiting as the invention may be variously embodied 95 and as the scope of such invention is to be determined as claimed.

I claim:

1. In a machine for producing a multi-folded package of paper, the combination of 100 means for initially folding the web longitudinally, means for severing the web into strips, mechanism for folding the severed strips transversely, and means for interfolding the previously folded strips to form a continuous package, consisting of engaged units, the last fold of each unit being overlapped by a portion of the succeeding unit.

2. In a machine for producing a multi-folded package of paper, means for initially folding a web, means for severing the web into strips, mechanism for transversely folding the severed strips, and means for interfolding the previously folded strips, consisting of opposed tucker blades, a stationary holder, a movable holder, means co-operating therewith for again folding the previously folded strips to form a continuous pack consisting of engaged units, the last fold of each unit being overlapped by 110 115 a portion of the succeeding unit.

3. A folding machine of the character described, comprising a main frame, a folder positioned therein for initially folding a web, mechanism for cutting and transversely 120 125 folding the web, mechanism for interfolding the previously folded units to form a package composed of folded units, the last leaf of each unit being overlapped by a portion of the succeeding unit.

4. In a folding machine of the character described, the combination of a main frame, means for initially folding a web, means for cutting the web into strips, means for transversely folding the severed strips, means for interfolding the previously folded strips to form a continuous package composed of units, the last leaf of which is overlapped by a portion of the succeeding unit.
5. In a machine for interfolding paper, the combination of means for folding a strip of paper longitudinally, a carrier roll for receiving the longitudinally folded paper, means cooperating with the carrier roll for severing the paper into sheets, creasing rolls for withdrawing the paper from the carrier roll and for transversely folding the paper, a stationary holder and a reciprocatory holder adapted to receive the transversely folded sheets, a pair of tucker blades mounted on opposite sides of said holders, and means for reciprocating said reciprocatory tucker blades to interfold the transversely and longitudinally folded sheets, whereby a stack of interfolded sheets is formed.
6. The method of producing a paper package comprising longitudinally folding a sheet of paper, severing the paper into lengths, transversely folding the severed lengths, and interfolding the transversely folded sheets to form a paper package with one lap of one sheet interfolded between the adjacent folds of the next sheet.
7. In a machine of the class described, the combination of means for longitudinally folding a strip of paper, a carrier roll for receiving the longitudinally folded strip, a cutter roll for severing the strips into lengths, a pair of creasing rolls having means for withdrawing the sheets from the carrier roll and forming a transverse crease at a point spaced from the center of the sheet, whereby a quadruple ply and a double ply is formed, and means for interfolding the transversely folded sheets and producing a fold in the quadruple ply and a fold in the double ply with the double ply inserted between the quadruple plies of a succeeding sheet.
8. In testimony that I claim the foregoing I have hereunto set my hand at Green Bay, in the county of Brown and State of Wisconsin.

PETER J. CHRISTMAN.
